CADDY-CART CLIP FOR HOLDING CIGARETTES, GOLF TEES, OR THE LIKE

Charles K. Wooden, Burbank, Calif.

Application November 14, 1947, Serial No. 142,517

Term of patent 14 years

(Cl. D17—3)

To all whom it may concern:

Be it known that I, Charles K. Wooden, a citizen of the United States and a resident of Burbank, California, have invented a new, original, and ornamental Design for a Caddy-Cart Clip for Holding Cigarettes, Golf Tees, or the like, of which the following is a specification, reference being had to the accompanying drawing, forming part thereof.

Referring to the drawing:

Figure 1 is a perspective view of a caddy-cart clip for holding cigarettes, golf tees, or the like, showing my new design;

I claim:

The ornamental design for a caddy-cart clip for holding cigarettes, golf tees, or the like, as shown.

CHARLES K. WOODEN.
